UNITED STATES PATENT OFFICE.

CHARLES W. REINOEHL, OF STEELTON, AND BENT L. WEAVER, OF MIDDLETOWN, PENNSYLVANIA; HELEN B. REINOEHL, OF STEELTON, PENNSYLVANIA, EXECUTRIX OF SAID CHARLES W. REINOEHL, DECEASED.

ANTICREEPER FOR RAILROAD-RAILS.

1,069,471.

Specification of Letters Patent.

Patented Aug. 5, 1913.

Application filed June 14, 1910. Serial No. 566,711.

To all whom it may concern:

Be it known that we, CHARLES W. REINOEHL, citizen of the United States, residing at Steelton, Dauphin county, State of Pennsylvania, and BENT L. WEAVER, citizen of the United States, residing at Middletown, Dauphin county, State of Pennsylvania, have invented certain new and useful Improvements in Anticreepers for Railroad-Rails, of which the following is a specification.

The object of our invention is to provide a novel, simple and efficient anticreeping device for railroad rails, which, when applied to the rail will prevent longitudinal displacement or creeping thereof.

To this end the invention, as generally stated, consists in providing an anticreeper having a part embracing one side of the base flange of the rail and engaging the top and the bottom of the base flange and the cross-tie and held in gripping position thereon and in constant readiness for action under all conditions by the spring action of one of the parts of the anticreeper in such manner that any tendency of the rail to creep will force the anticreeper into firmer engagement with the rail and prevent the creeping thereof, as will be hereinafter fully described and claimed.

In the drawings:—Figure 1 is a plan view of a portion of a railroad cross-tie, a railroad rail thereon and one form of an anticreeper embodying our invention applied thereto. Fig. 2 is an end elevation of the parts shown in Fig. 1. Fig. 3 is a side elevation of the parts shown in Fig. 1. Fig. 4 is a plan view of a portion of a railroad cross-tie, a railroad rail thereon and another form of an anticreeper embodying our invention applied thereto. Fig. 5 is a side elevation of the parts shown in Fig. 4. Fig. 6 is an end elevation of the parts shown in Fig. 4. Fig. 7 is a plan view of a portion of a railroad cross-tie, a railroad rail thereon and another form of an anticreeper embodying our invention applied thereto. Fig. 8 is a side elevation of the parts shown in Fig. 7. Fig. 9 is an end elevation of the parts shown in Fig. 7.

Referring first to Figs. 1, 2 and 3, 2 designates a cross-tie and 3 a railroad rail supported thereon. The rail 3 is of usual con-

struction including the base flange 4. Engaged with the cross-tie 2 and rail 3, is an 55 anticreeper 5, the same being one form of embodiment of our invention and of the following construction:—Embracing one side of the base flange 4 is a part 6 including an upper portion 7 extending over and engaged 60 with the top of the base flange 4, a lower portion 8 extending under and engaged with the bottom of the base flange 4, and a loop 9 extending around the edges of the base flange 4 and connecting the upper and lower 65 portions 7 and 8. Extending upwardly and then rearwardly and then downwardly from the inner end of the upper portion 7 of the part 6 is a part 10, the rearward end of which is in engagement with the upper face 70 of the base flange 4. The lower portion 8 of the part 6 is connected to a part 11 by a centrally-arranged loop 12, the part 11 being located in line with the part 8 and directly beneath the opposite side of the base flange 75 4. The outer end of the part 11 is provided with a hook or loop 13, which embraces the side of the base flange 4 opposite to the side embraced by the part 6, thus holding the anticreeper in place upon the rail and preventing the part 6 from being displaced laterally from its position upon the base flange 4.

In applying the anticreeper 5 to the rail 3, the parts 6 and 10 are first applied to one 85 side of the base flange 4 whereupon the hook or loop 13 may be sprung outwardly owing to the central loop 12 and then engaged with the base flange 4, after which it will be held in firm engagement therewith by the spring 90 action of the loop 12. Normally, or before the anticreeper 5 is applied to the base flange 4, the rearward end of the part 10 is below its point of engagement with the base flange 4, while the remaining parts of the anti- 95 creeper 5 are in the positions shown in the drawings; and, when the anticreeper is applied to the base flange 4, the rearward end of the part 10 is sprung upwardly to permit the part 6 to be passed over and embrace one 100 side of the base flange 4, after which the spring action of the part 10 will exert a forward pressure against the upper portion 7 of the part 6, and a rearward pressure against the lower portion 8 of the part 6, 105 thereby causing the portions 7 and 8 of the

part 6 to bind against the upper and lower faces respectively of the base flange 4, and hold the part 6 in gripping position thereon. When the anticreeper 5 is applied to the rail 3, as just described and as shown in the drawings, the forward faces of the parts 8, 11 and 12 are in engagement with the side of the cross-tie 2. It will thus be seen that should the rail 3 attempt to creep forwardly or in the direction of the arrows shown in Figs. 1 and 3, the lower portion 8 of the part 6 will be prevented from moving by the parts of the anticreeper engaged with the cross-tie 2. It therefore follows that the instant the rail 3 attempts to creep forwardly, it will tend to carry the upper portion 7 of the part 6 with it and thereby cause the part 6 to increase its grip upon the base flange 4 and prevent the rail 3 from creeping.

By the construction just described, it will be seen that the anticreeper 5 is firmly held in engagement with the rail 3 by the spring action of parts of the anticreeper, and that the spring action of said parts will compensate for any expansion and contraction of the metal, and hold the anticreeper in gripping position and in constant readiness for action under all conditions.

Referring now to Figs. 4, 5 and 6, showing a modification of our invention, 2 designates a cross-tie and 3 a rail, the same as shown in Figs. 1, 2 and 3; and 14 designates a modified form of our anticreeper, which is of the following construction:—Located on one side of the rail 3, is a member 15, which is formed from a blank of sheet steel and comprises a body portion 16, a forward end portion 17 and an arm or part 18. The body portion 16 is arranged parallel to and in engagement with the edge of the base flange 4, the part 17 extends substantially at right angles to the body portion 16 and embraces one side of the base flange 4 and is engaged with the upper and lower faces thereof. The part 18 extends rearwardly and downwardly from the top of the part 17, and the rearward end of the part or arm 18 bears against the top of the base flange 4. It will thus be seen that the parts of the member 15, as a whole, embrace and engage one side of the base flange 4. In order to hold the member 15 in place and prevent it from being displaced laterally from the rail 3, we provide a spike 19, which is driven into the cross-tie 2 adjacent the outer face of the body portion 16 of the member 15. Normally, or before the anticreeper 14 is applied to the base flange 4, the rearward end of the part or arm 18 is below its point of engagement with the base flange 4, while the remaining parts of the anticreeper 14 are in the positions shown in the drawings, and when the anticreeper is applied to the base flange 4 the rearward end of the part 18 is sprung upwardly to permit the part 17 to be

passed over and embrace one side of the base flange 4, after which the spring action of the part 18 will exert a forward pressure against the upper portion of the parts 16 and 17, and a rearward pressure against the lower portion of the parts 16 and 17, thereby causing the upper portion of the part 17 to bind against the upper face of the base flange 4, and the lower portion of the part 17 to bind against the lower face of the base flange 4 and hold the anticreeper in gripping position upon the rail. When the anticreeper 14 is applied to the rail 3, as just described, and as shown in the drawings, the forward face of the lower portion of the part 17 is in engagement with the side of the cross-tie 2. It will thus be seen that should the rail 3 attempt to creep forwardly, or in the direction of the arrows shown in Figs. 4 and 5, the lower portion of the part 17 will be prevented from moving by its engagement with the cross-tie 2. It therefore follows that the instant the rail 3 attempts to creep forwardly, the upper face of the base flange 4 will tend to carry the upper portion of the part 17 with it, and thereby cause the part 17 to increase its grip upon the base flange 4 and prevent the rail 3 from creeping.

Referring now to Figs. 7, 8 and 9, showing another modification of our invention, 2 designates a cross-tie and 3 a rail, the same as shown in Figs. 1, 2 and 3; and 20 designates a modified form of our anticreeper, which is of the following construction:—21, 21 are two members formed of sheet steel, and these members are identical in construction with the member 14, shown in Figs. 4, 5 and 6, with the exception that one member 21 is oppositely disposed with relation to the other member, one member 21 embracing and engaging one side of the base flange 4, and the other member 21 embracing and engaging the other side of the base flange 4; and, with the further exception that the members 21 are made lighter than the member 14 by reason of the employment of two members instead of a single member. These members 21 are held in place upon the base flange 4 and prevented from being displaced laterally therefrom by a suitable bolt 22 extending through the body portion 16 of the members 21. The members 21 are held in gripping position upon the base flange 4 and are engaged with the cross-tie 2, and prevent the creeping of the rail 3 precisely like the member 14 shown in Figs. 4, 5 and 6, and no detailed description thereof is deemed necessary in view of the description of the member 14.

We desire it to be understood that the constructions herein shown and described may be still further modified without departing from our invention.

One of the important features of our in-

vention to which we broadly lay claim, is the employment of a part engaging the upper and lower faces of the rail base flange and held in gripping position thereagainst by the spring action of one of the parts of the anticreeper and having its lower portion engaging a cross-tie and causing it to increase its grip upon the rail.

We claim:—

4

anticreeper provided with a part embracing one side of said base flange and engaging the top and bottom thereof, the lower portion of said part engaging said cross-tie, 5 spring pressed means exerting forward pressure against the upper portion of said part and rearward pressure against the lower portion of said part and holding said part in gripping engagement with said base flange, and a second part projecting from the first named part and having a loop formed therein below the rail and embracing the other side of the base flange.

10. The combination of a cross-tie, and a railroad rail having a base flange, of an anticreeper provided with a part embracing one side of said base flange and engaging the top and bottom thereof, the lower portion of said part engaging said cross-tie, a 15 spring pressed arm projecting from said part and engaging the top of said base flange and exerting forward pressure against the upper portion of said part and rearward pressure against the lower portion of said part and holding said part in gripping engagement with said base flange, and a second part projecting from the first named part and having a loop formed therein be-

low the rail and embracing the other side of the base flange. 30

11. An anti-creeping device including a rail engaging member adapted to grip the rail when canted, and a spring arm projecting from the rail engaging member and bearing against the rail for holding the said rail engaging member yieldingly in a canted position. 35

12. An anti-creeping device including a clip adapted to loosely receive the flange of a rail, and yielding means for normally holding the clip in a position canted from a vertical plane for causing the said clip to grip the rail. 40

13. An anti-creeping device including a clip adapted to loosely receive the base flange of a rail, and a spring arm projecting from one jaw of the clip and bearing loosely against the rail so as to hold the clip yieldingly in a canted position. 45

In testimony whereof we affix our signatures in the presence of two witnesses.
